UNITED STATES PATENT OFFICE

EDWARD P. DONNELLAN, OF BROOKLYN, NEW YORK, ASSIGNOR TO STANDARD-JOHNSON COMPANY, INC., OF BROOKLYN, NEW YORK, A CORPORATION OF NEW YORK

FEEDER ATTACHMENT FOR COIN COUNTING MACHINES

Application filed July 7, 1930. Serial No. 466,076.

This invention relates, generally, to improvements in coin counting machines and other machines to which it is desired to feed coins or other articles subject to the machine 5 functions; and, the invention has reference, more particularly, to a novel automatic means for delivering said coins or other articles to the operative parts of the machine, during operation thereof.

10 This invention has for its principal object to provide a supply hopper or magazine of novel form having in cooperative relation thereto a novel rotary conveyer means for transferring coins or other articles from the 15 hopper or magazine to the machine desired to manipulate the same.

Other objects of this invention, not at this time more particularly enumerated, will be understood from the following detailed de-

20 scription of the same.

An illustrative embodiment of the novel feeder means made according to the principles of this invention is shown in the accompanying drawings, in which:—

25 Figure 1 is a top plan view of a coin counting machine provided with the novel feeder means of this invention; Figure 2 is a vertical section of the same, taken on line 2—2 in Figure 1; Figure 3 is a vertical section of the 30 same, taken on line 3—3 in Figure 1, but drawn on an enlarged scale; and Figure 4 is a detail perspective view of the rotary conveyer device which forms a part of said novel feeder means.

35 Similar character of reference are employed in the above described views, to indicate corresponding parts.

Referring to said drawings, the reference character 5 indicates the centrifugal rotatable delivery table which arranges the coins and delivers the same in a moving train to the coin counting mechanism per se. This table 5 is bounded by the coin guiding wall 6, in connection with which is provided the 45 usual coin escape passageway leading to the propeller wheel 7, which forces the coins into operative engagement with the star wheel 8 of the coin counting register 9. Said table 5 is mounted with its upper surface flush with

the bed-plate 10 of the machine. The bed-plate 10 is supported on suitable standards 11.

Journalized beneath the bed-plate 10 of the machine is a drive shaft 12, which may be itself driven by any suitable means, either by hand or by power. A worm 13 on said shaft 12 meshes with a worm wheel 14 on the vertical spindle of said table 5, whereby the latter is operatively rotated.

Connected with the bed-plate 10 by means of supporting brackets 15, so as to be off-set from a side thereof, and so as to be disposed preferably in a vertical plane, is an annular housing 16. This housing 16 is closed by a face wall 17 extending along the side or face thereof which lies toward the counting machine. Said face wall 17 is provided in its upper portion with an escape opening 18.

Journalized in a central bearing opening 19 provided in said face wall 17 is a rotatable spindle 20 on which is fixed a conveyer wheel 21, which fits and rotates within said annular housing 16. Said conveyer wheel 21 is pro-

vided with a plurality of circumferentially spaced pockets formed by radial arms 22. Said pockets are open from side to side of said conveyer wheel, and at their inner ends are bounded by inclined bottom portions 23,

which slope from the outer face of the conveyer wheel to the inner face thereof which opposes the counting machine. Secured to the inner side of the annular housing 16, so as to partially cover the rear face of said conveyer wheel is cover plate 24, which leaves the pockets thereof rearwardly open, however, as the same are carried downwardly toward the lower portion of the annular housing during the rotation of the conveyer wheel.

Secured to the annular housing 16 is a hopper or magazine 25, which is provided with a downwardly and inwardly sloping bottom 26 extending toward the outer or rear face of the conveyer wheel.

Said conveyer wheel 21 is driven from the drive shaft 12 of the counting machine by a suitable transmission means including a clutch means for starting and stopping the rotation of said conveyer wheel at will.

Preferably said transmission means comprises the following arrangement:—

Journalized in bearings 27, which are affixed to the under side of the bed-plate 10 of the counting machine, so as to depend therefrom, is a counter shaft 28. Fixed on said counter shaft 28 is a worm gear 29 which meshes with and is driven by a worm 30 fixed on said drive shaft 12. Fixed on said counter shaft 28 is a male clutch-member 31. Rotatable on the opposite end of said counter shaft 28 is a hollow shaft or sleeve 32, and keyed to this latter is a shiftable female clutch member 33 adapted to be moved 15 into and out of engagement with said male clutch-member 31 to couple or uncouple said hollow shaft or sleeve 32 in driven relation to said counter shaft 28. Fixed on said hollow shaft or sleeve 32 is a bevel gear 34. 20 Journaled in a bearing 35, which is secured to said bed-plate 10, is a spindle 36, having fixed thereon a bevel gear 37 to mesh with and be driven by said bevel gear 34. Fixed on the outer end of said spindle 36 is a pulley 38 over which runs a drive belt 39, which in turn runs over and drives a second pulley wheel 40 fixed on the conveyer wheel spindle 20.

Suitable means for operating the clutch mechanism is provided, the same preferably comprising a slide bar 41, mounted to slide through the bearings 27 parallel to and preferably above the counter shaft 28. Secured to said slide bar 41 is a shifter yoke 42, the arms 43 of which operatively engage in the annular channel 44 provided in the body of said female clutch-member 33. A compression spring 45 interposed between said shifter yoke 42 and the forward bearing 27 yieldably 40 holds said female clutch-member disengaged from said male clutch-member. Pivots connected with the forward end of said slide bar 41 is a draw link 46 which extends outwardly and forwardly to the front of the counting machine. Said draw link terminates in a knob or hand grip 47. Provided in the body of said draw link 46, adjacent to its outer end, is a notch 48, which, when the draw link is pulled forward to draw the slide-bar and shifter yoke to clutch engaging position, may be hooked over a fixed stop bracket 49, to thereby retain the parts in clutch engaging position against the tension of the spring 45. When it is desired to release the clutch, the operator merely swings up the draw link 46 to disengage its notch 48 from the stop bracket 49, whereupon the spring 45 will force back the slide-bar and shifter yoke to clutch releasing position.

Pivots connected to perforate ears 50 with which the annular housing 16 is provided, are the side arms 51 of a chute 52, which is disposed to extend from the escape opening 18 inwardly over the delivery table 5 of the counting machine, when the same is

lowered to operative position. The free end of said chute 52 may be provided with a cover hood 53 to form a spout-like portion, which overhangs the delivery table 5 of the counting machine, and which prevents misdelivery 70 of coins or other articles passed therethrough. The chute device, as thus mounted and arranged, may be upturned to an inoperative position giving unobstructed access to the delivery table 5 and guide wall 6 of the counting machine, when such is desired.

In operation, a mass of coins to be counted are deposited in the interior of the magazine or hopper 25, the sloping bottom wall of which causes the coins to gravitate toward 80 the rearwardly exposed portions of the conveyer wheel. Power is now applied to the drive shaft 12, whereby the rotatable delivery table 5 is caused to revolve. The clutch means 31—33 being engaged by pulling out 85 and locking the draw link 46, power is likewise transmitted to the conveyer wheel 21, which is caused to rotate in the direction of the arrow shown in Figure 3. As the conveyer wheel 21 revolves, its pockets are successively carried past the rearwardly open portion of the housing 16 where uncovered by the cover plate 24, so that communication is established between the thus moving 90 pockets and the interior of the hopper or 95 magazine, whereby coins will fall into the said pockets. The coins thus engaged in the pockets of the conveyer wheel will be carried upward by the rising pockets, being retained against escape from the latter as the same are 100 carried between the face wall 17 and cover plate 24, until the pockets pass into alignment with the escape opening 18, whereupon, owing to the downward and inward pitch or inclination of the bottoms 23 of the pockets, 105 the coins will slide forwardly and outwardly from the pockets onto the chute 52 by which the same are guided to and thrown upon the revolving delivery table 5 of the coin counting machine. Since each pocket will contain 110 but comparatively few coins, and since the pockets by continuous rotation of the conveyer wheel are successively carried past the point of coin pick-up and then the point of coin discharge, it follows that the coins will 115 be continuously delivered to the feed table 5 of the machine approximately in about the same numbers as are fed away to the counting mechanism by the operation of the feed table 5. If, by any chance, however, the delivery of coins to the feed table 5 by the conveyer wheel 21 should excessively gain upon the rate of discharge thereof by the feed table, the operator may release the clutch-mechanism 120 so as to temporarily stop the conveyance of coins, until consumption thereof has reduced the quantity within the guide ring 6 and upon the table 5, whereupon by again manipulating the clutch the operation of the conveyer wheel may be resumed.

The advantages of the novel coin supplying means in connection with the counting machine will be obvious. It will be understood also that the feeder attachment is, per 5 se, capable of use with other mechanisms to which it is desired to continuously supply small articles subject to a desired manipulation or operation.

I am aware that many changes could be 10 made in the above described mechanism as well as in the details of the construction thereof, without departing from the scope of this invention, and therefore it is intended that all matter contained in the above description or 15 shown in the accompanying drawings shall be interpreted as illustrative and not in a limiting sense.

I claim:—

1. In a coin counting machine having a 20 centrifugal table operative to arrange coins in a train for successive delivery to counting mechanism, a hopper to contain a quantity of coins to be counted, a transversely open pocketed conveyer wheel rotatable in 25 a vertical plane with the rear side thereof contiguous to the hopper interior so as to receive coins therefrom, means to partially cover said rear side of said conveyer wheel to limit the area of communication between 30 the pockets thereof and the hopper interior, a closing wall contiguous to the forward side of said conveyer wheel, said wall having an escape opening with which the pockets of 35 the conveyer wheel successively communicate, and a pivoted discharge chute movable from an up-turned inoperative position to a down-swung operative position extending from said escape opening over said counting machine table.

40 2. In a coin counting machine having a centrifugal table operative to arrange coins in a train for successive delivery to counting mechanism and a power transmission means for actuating said table and counting 45 mechanism, a hopper to contain a quantity of coins to be counted, a transversely open pocketed conveyer wheel rotatable in a vertical plane with the rear side thereof contiguous to said hopper interior so as to receive coins therefrom, means to partially cover said rear side of said conveyer wheel to limit the area of communication between the pockets thereof and the hopper interior, 50 a closing wall contiguous to the forward side of said conveyer wheel, said wall having an escape opening with which the pockets of the conveyer wheel successively communicate, transmission means for rotating said conveyer wheel, means to connect at will said wheel transmission means in driven relation to said machine transmission means, and a pivoted discharge chute movable from an up-turned inoperative position to a down-swung 55 60 65 operative position extending from said es-

cape opening over said counting machine table.

In testimony that I claim the invention set forth above I have hereunto set my hand this 18th day of June, 1930.

EDWARD P. DONNELLAN.
